(57) **CLAIM**

The ornamental design for a spring handle between arms, as shown and described.

DESCRIPTION

FIG. 1 is a top perspective view of a spring handle between arms according to the present invention.

FIG. 2 is a bottom perspective view of the spring handle between arms of FIG. 1.

FIG. 3 is a top view of the spring handle between arms of FIG. 1.

FIG. 4 is a bottom view of the spring handle between arms of FIG. 1.

FIG. 5 is an end view of the spring handle between arms of FIG. 1.

FIG. 6 is a left side view of the spring handle between arms of FIG. 1; and,

FIG. 7 is a right side view of the spring handle between arms of FIG. 1.

The broken lines immediately adjacent the shaded areas represent the bounds of the claimed design while all other broken lines are directed to environment and are for illustrative purposes only; the broken lines form no part of the claimed design.

1 Claim, 4 Drawing Sheets
